[57] ABSTRACT

A free-flooding magnetostrictive scroll transducer and method of making it. The transducer construction allows free-flooding water to fill the scroll interstices, thus eliminating the need for bonding of proximate layers of magnetostrictive material with a resinous material, as considered necessary in making a conventional scroll transducer.

SCROLL TRANSDUCER

STATEMENT OF GOVERNMENT INTEREST

The invention described herein may be manufactured and used by or for the Government of the United States of America for governmental purposes without the payment of any royalties thereon or thereafter.

BACKGROUND OF THE INVENTION

This invention relates to novel advantageous electro-acoustic transducers in general and more particularly to free-flooding magnetostrictive scroll transducers.

In one type of magnetostrictive scroll transducer, the magnetostrictive core is formed by bonding adjacent layers of a magnetostrictive strip material with a fluid resinous material, forming essentially a laminated core to reduce eddy currents. It was found necessary to use a resinous material to maintain a uniform distance between two adjacent layers so that the transducer will exhibit uniform characteristics. One such transducer is described in U.S. Pat. No. 3,393,401 to Theodore J. Meyers. However, consolidation of the magnetostrictive material with the resinous material and curing the resinous material in the interstices of various layers required expensive tooling. Furthermore, the vapors of the resinous materials used are hazardous to the health of fabricators.

SUMMARY OF THE INVENTION

The objects and advantages of the present invention are accomplished by utilizing a free-flooding magnetostrictive scroll transducer wherein water is substituted for resinous materials used for bonding proximate layers of magnetostrictive material and maintaining a uniform spacing therebetween. The water used acts as a lubricant and fills interstices between the scroll layers and also reduces the distance between the scroll layers. Should this water evaporate when the transducer is in storage, the reduced size interstices act as capillaries which are filled with water during a short soaking period of the transducer. The transducer is thus operated with water filling the volume in between the scroll layers and thus making it a truly free-flooding unit.

One object of this invention is the elimination of the use of resinous materials (such as epoxy), materials heretofore deemed indispensable, for bonding proximate layers of a scroll type magnetostrictive transducer and maintaining a uniform distance therebetween, thus reducing the cost of tooling.

Another object is to reduce a health hazard to fabricators by eliminating the use of a fluid resinous material which produces toxic fumes during use.

Still another object is the use of water in the interstices which, resonating with the transducer element, acts as a rigid solid during operation and thus improves the performance of the scroll transducers of this invention.

A further object is to provide structure adapted to improve the frequency response of scroll transducers.

Other objects, advantages and novel features of the invention will become apparent from the following detailed description of the invention when considered in conjunction with the accompanying drawings wherein:

BRIEF DESCRIPTION OF THE DRAWINGS

FIG. 1 is a perspective view, partly broken away, of an electroacoustic transducer having a scroll type core, showing a preferred embodiment of the invention;

FIG. 2 is a cross section along line 2-2 of FIG. 1; and

FIG. 3 is a cross section along line 3-3 of FIG. 1.

DESCRIPTION OF A PREFERRED EMBODIMENT

A free-flooding magnetostrictive scroll type transducer, shown in FIG. 1, is designated by numeral 10. The transducer 10 comprises a cylindrical core 12 which can be of spherical shape. However, the shape of the core is not a significant part of this invention. The core is made of a magnetostrictive material, generally a thin strip of nickel and has the same cross section all the way around. The core comprises a plurality of layers of the strip which are designated as a group by numeral 14 in FIG. 1. A first ring 16, formed by soft welding one end 18 of the strip to the end of the first or the innermost layer or convolution 20 of the core, defines the inner diameter of the core. The remaining layers of the core are formed by coiling the nickel strip around the first layer 20. These layers are spaced. The nickel strip forming the core is then placed on a heat insulator, such as an alundum bat, and annealed at a high temperature, preferably around 800° C. This treatment gives the nickel strip desired magnetic properties and produces a thin coating of nickel oxide on the exposed surfaces of the strip. The nickel oxide coating is then used to electrically insulate two adjacent layers from each other.

The inner circumference of the nickel core is then positioned and secured on the outer diameter of a wooden mandrel (not shown in the drawings) with each layer loosely coiled on its inner neighbor. Holding wires are then attached to the outer tab of the nickel strip and the core is mounted in a tightening tank (not shown in the drawings) which is a tank having water therein to cover the loose scroll. A detergent is added to the water in the tightening tank to act as a lubricant. The scroll is then excited and tightened. The scroll is then removed from the tank, and the outer tab of the scroll is silver soldered to the proximate layer and the wooden mandrel is pulled out of the tightened scroll. A layer 22 of epoxy impregnated fiber glass tape is then applied, covering the outer layer of the scroll as shown in FIG. 2.

A continuous length of a waterproof insulated conductor 24 is then tightly coiled around the magnetostrictive core, engaging the layers of the core 12. The two ends of the conductor are connected to signal generating equipment as is conventional. As shown in FIG. 3, a plurality of interstices, such as one designated by numeral 26, are thus formed between two adjacent layers of the nickel strip of which the scroll is made.

After fabrication, and prior to any acoustic evaluation, a scroll transducer is kept submerged in water to prevent interlayer desiccation. However, interstitial water usually evaporates in due course of time, leaving only air between different layers. Interstitial water is supplied by immersing the transducer in water before an acoustic evaluation thereof. During the course of acoustic evaluation of a free-flooding scroll transducer fabricated according to the teachings of this invention, it has been found that its sensitivity, transmitting fre-

quency response, and receiving frequency response are at least as good as such characteristics of a conventional free-flooding scroll transducer.

Thus a truly free-flooding transducer is described which is fabricated by using a strip of a magnetostrictive material, such as nickel. One end of the strip is soft welded forming an inner layer and the remaining layers are formed thereon. Before exciting and tightening the layers of the strip in a water tank, the strip is annealed at a high temperature to form a coating of oxide which insulates electrically proximate layers of the strip. The tightened scroll, so formed, has interstices between layers which are occupied by water instead of epoxy as in conventional transducers, thus making the transducer truly free-flooding. The shape of the transducer is maintained by applying a layer of epoxy impregnated fiber glass tape around the outermost layer of the scroll. A continuous length of a waterproof insulated conductor is tightly coiled around the core of the scroll and its ends are connected to a signal generating equipment.

Obviously many modifications and variations of the present invention are possible in the light of the above teachings. It is therefore to be understood that within

the scope of the appended claims the invention may be practiced otherwise than as specifically described.

I claim:

1. A free-flooding scroll type magnetostrictive transducer comprising:

a coiled core of continuous magnetostrictive strip material defining a torus, said core being of an approximately uniform cross section normal to a part of the circumference of said torus and providing a plurality of layers having fluid filled interstices therebetween; and

a conductor toroidally coiled around said core.

2. The transducer of claim 1 wherein said conductor is waterproof and electrically insulated.

3. The transducer of claim 2 wherein the surface of said magnetostrictive material is oxidized for electrically insulating proximate layers of said scroll from each other.

4. The transducer of claim 2 wherein the width of said strip material is smaller than the inner diameter of said core.

5. The transducer of claim 2 wherein the magnetostrictive material is nickel.
